CLAIM

The ornamental design for a brush head as shown and described.

DESCRIPTION

FIG. 1 is a top front-left perspective view of a brush head; FIG. 2 is a left side elevation view thereof, of which the right side elevation view thereof is a mirror-image;

FIG. 3 is a top plan view thereof;

FIG. 4 is a front elevation view thereof;

FIG. 5 is a rear elevation view thereof;

FIG. 6 is a bottom plan view thereof; and,

FIG. 7 is a bottom front-left perspective view thereof.

The broken lines in the drawing figures depict portions of the brush head that form no part of the presently claimed design.
